UNITED STATES PATENT OFFICE.

HARLEY A. W. HOWCOTT, OF NEW ORLEANS, LOUISIANA.

IGNITER FOR INTERNAL-COMBUSTION ENGINES.

Application filed January 15, 1926. Serial No. 81,485.

This invention relates to improvements in internal combustion engines, but more specifically to the igniting apparatus thereof, and it consists of the constructions, combinations and arrangements herein described and claimed.

An object of the invention is to provide an abrasive wheel in the combustion chamber of an internal combustion engine and 10 a co-acting contactor which is engageable with the wheel when the ignition period of the engine arrives, there being a counter shaft from which the wheel is revolved at a sufficiently high rate of speed and from 15 which reciprocatory motion of the contactor is derived.

Other objects and advantages appear in the following specification, reference being had to the accompanying drawing, in which

20 Figure 1 is a plan view of the igniter apparatus enough of the engine block being shown to illustrate the relationship thereto of the igniter.

25 Figure 2 is a detail perspective view illustrating details of the contactor.

Figure 3 is a detail perspective view of a portion of the cylinder head illustrating one of the screw tops through which access may be had for replacing the contactor.

30 Figure 4 is a vertical cross section of the engine taken substantially on the line 4—4 of Figure 1 but illustrating the engine parts in full lines, the piston having reached the limit of compression and the igniter being 35 ready to fire a charge.

Figure 5 is a detail perspective view showing only such parts as are concerned directly with the igniter.

The internal combustion engine to which 40 the igniter is applied is to be regarded as of conventional construction. Briefly described, the engine comprises the cylinder block 1 which has a number of cylinder bores or combustion chambers 2. A piston 45 3 is reciprocated in each of the bores by the rod 4 which connects it with the crank 5 of the main shaft 6. The cylinder block has a cover or head 7 which, for the purposes of the invention, is provided with an opening 50 8 which is fitted with and normally closed by the screw top 9 (Fig. 3). This opening may be regarded as replacing the ordinary spark plug opening, but in this instance should be made of sufficiently large size so 55 that access may be had to the interior for replacement of the contactor to be described.

A sprocket 10 on the main shaft 6 drives the sprocket 11 of the countershaft 12 by means of a chain 13. The countershaft 12 might be driven by gears, but in view of the distance between the main and countershafts it is deemed preferable to employ the sprocket and chain connections. The countershaft 12 is suitably journaled at 14 upon the engine block, and in practice a lubricant 60 will be conducted to the various bearings by any one of the known methods.

A second sprocket 15 on the countershaft 12 (Fig. 1) drives a shaft 16, which is parallel to the countershaft 12, through a chain 17. The function of the shaft 16 suggests the term "igniter shaft" by which it is herein distinguished. The igniter shaft carries a sprocket 18 to which the chain 17 is applied so that the igniter shaft is revolved 70 simultaneously with the countershaft 12.

The igniter shaft carries a plurality of abrasive wheels 19, there being one for each engine cylinder. The igniter shaft is so journaled upon the cylinder block that the 75 abrasive wheels occupy and revolve in the respective combustion chambers.

The igniter shaft is preferably so journaled that the cylinder head 7 may be removed without impediment. Appropriate 80 bearings for the igniter shaft must be provided and these, in turn, will be lubricated by any suitable and known method. The wheels 19 will be of any suitable abrasive material that will strike sparks when 85 touched by a metallic substance during revolution. Emory, carborundum, etc. may be employed.

The countershaft 12 has a plurality of 90 cranks 20, one for each engine cylinder. Each crank has connection by means of a link 21 with a rod 22 which extends through the cylinder block and terminates in a socket 23. The socket is equipped with a bolt 24 by means of which the shank 25 of the contactor 26 is rigidly held. The shank is non-circular in cross section and fits a corresponding opening in the socket 23, the arrangement preventing slipping around of 95 the shank.

The contactor is metallic, and upon reciprocation of the rod 22 the point of the contactor comes into periodic engagement with the surface of the abrasive wheel 19 producing sparks for the ignition of a charge in the combustion chamber of the engine. The contactor is movably mounted at 100 105 110

28 upon the shank 25, for example by means of a hinge arrangement. A leaf or other spring 29, carried by the shank, presses the contactor outwardly so that effective engagement will be made with the abrasive element even though the contactor has become considerably worn.

10 The exposed extremity of the rod 22 is bifurcated at 27 (Fig. 2) to conveniently make connection with the link 21. The rod 22 may be made round where it passes through the cylinder wall so that it may be packed (packing not shown) to prevent compression leaks. In practice the bolt 24 can be tightened and loosened by the insertion of an appropriate instrument, for example pliers or a wrench, through the adjacent opening 8.

15 The operation is readily understood. The engine selected for illustration is of the four-cylinder, four-cycle type. In order that the contactor 26 may engage the surface of the abrasive wheel 19 at the ignition period it is necessary to revolve the countershaft 12 at half the main shaft speed. In other words, the 20 countershaft 12 makes one revolution to two revolutions of the main shaft 6. The sprockets 10 and 11 are proportioned to achieve this result. But it is preferable that the abrasive wheel 19 shall revolve at a rather 25 high rate of speed, and the sprocket 18 must therefore be smaller than the sprocket 13 which drives the igniter shaft 16.

30 Assume the piston 3 of the cylinder nearest to the chain 13 and 17 as having reached the limit of a compression stroke (Fig. 4). The respective crank 20 of the countershaft 12 will at this time be in position to have thrust the rod 22 to the limit of its inward 35 stroke thereby bringing the contactor 26 into engagement with the surface of the rapidly revolving abrasive wheel 19. The resulting sparks ignite the compressed charge, and the piston 3 travels the working stroke.

40 It is observed that the cranks 20 of the countershaft 12 are arranged at quarters so that the cylinders will fire in the order 1, 3, 4, 2. The left end of the cylinder block (Fig. 1) is considered the front of the engine. Ignition is occurring in the combustion 45 chamber of cylinder #4. The abrasive wheels 19 and the coating contactors 26 operate solely within the combustion chamber of each cylinder. The igniter rod 22 has 50 slidable bearing upon the cylinder block 1. The countershaft 12 serves the combined 55 purposes of reciprocating the contactor 26 and revolving the abrasive wheel 19.

60 The main shaft 6 revolves in the clockwise direction looking at the engine from the front. By tracing the chain connections with the igniter shaft 16 it is observed that the latter also revolves in the clockwise direction. The latter direction of revolution of the igniter shaft is intentional. The engagement of the contactor 26 with the sur-

70 face of the abrasive element or wheel 19 then produces a stream of sparks in the downward direction, in other words, directly into the combustible charge so that the charge is ignited most effectively.

75 While the construction and arrangement of the improved igniter is that of a generally preferred form, obviously modifications and changes may be made without departing from the spirit of the invention or the scope 80 of the claims.

I claim:—

1. In combination with an engine cylinder having a piston operable therein to form a combustion chamber, an abrasive element situated solely and revoluble within the combustion chamber, a metallic contactor also situated solely within the combustion chamber, and means carrying the contactor being reciprocatively mounted in the cylinder wall for periodically engaging the contactor with the surface of said element.

2. In combination with a cylinder block having a cylinder and a piston operable within the cylinder to form a combustion chamber, an abrasive element situated solely and revoluble within the combustion chamber, a contactor also situated within the combustion chamber being engageable with the abrasive element to produce sparks within said chamber, means carrying the contactor having bearing support upon the cylinder block, and means for reciprocating said carrying means for the purpose described.

3. In combination with a cylinder block 100 having a cylinder and a piston reciprocable in the cylinder to form a combustion chamber, a revoluble abrasive element situated solely within the combustion chamber, a rod projecting through the cylinder block 105 which thereby affords a slidable bearing, one end of the rod being exposed in the combustion chamber the other being exposed on the outside, a contactor carried by that end of the rod exposed in the combustion chamber, and revoluble means having such connection with the other end of the rod as to reciprocate said rod in its bearing to periodically engage the contactor with said abrasive element.

4. In combination with a cylinder block having a cylinder, and a piston operable therein to form a combustion chamber, an igniter shaft journaled upon the cylinder block to pass through the combustion chamber, an abrasive element carried by the shaft and situated solely within the chamber, a rod passing through the cylinder block which thereby provides a bearing one end of the rod projecting into the combustion chamber the other end being exposed on the outside, means on the inner end of the rod detachably carrying the contactor, a countershaft having driving connection with the ignited shaft for revolving the abrasive 115 120 125 130

element, and a crank formed in the counter-shaft having a link connection with the exposed end of the rod for simultaneously reciprocating the rod in its bearing and causing periodic engagement of the contactor with the surface of said element.

5. In combination with a cylinder block having a cylinder, a main shaft, and a piston operable in the cylinder to form a combustion chamber; an igniter shaft journaled upon the block to pass through the combustion chamber, an abrasive element carried by said shaft being situated in the chamber, a contactor also in the chamber, means carrying the contactor extending through the cylinder block which thereby provides a bearing, a countershaft journaled upon the cylinder block, means for driving the countershaft from the main shaft and in turn driving the igniter shaft from the countershaft so that the igniter shaft revolves simultaneously with the main shaft, and a crank formed in the countershaft having a link connection with the exposed end of said contact-carrying means to produce simultaneous reciprocation of the contactor and periodic engagement thereof with said abrasive element.

6. In combination with an engine cylinder having a piston operable therein to form a combustion chamber, a metallic contactor reciprocable in the combustion chamber, an abrasive element also in the chamber and

with which said contactor is periodically engageable, and means for revolving said abrasive element in a direction to throw a stream of sparks toward the head of the piston upon engagement of the contactor.

7. In combination with a cylinder block having a cylinder, a cylinder head and a piston operable in the cylinder defining a combustion chamber; a continuously revoluble abrasive element situated solely within the combustion chamber, a reciprocable rod having bearing on the cylinder block and terminating in a socket on the combustion chamber end, a contactor seated in the socket and being periodically engageable with the abrasive element, means detachably securing the contactor in said socket, and a screw top occupying an opening in the cylinder head, the removal of the screw top permitting the insertion of a tool for loosening said securing means preparatory to exchanging the contactor.

8. Apparatus of the character described comprising a revoluble abrasive element, reciprocable means having a non-circular opening, a correspondingly non-circular shank fitting said opening, a contactor movably mounted upon the shank and being periodically engaged with said element, and resilient means bearing against the contactor insuring engagement thereof with said element.

HARLEY A. W. HOWCOTT.
